UNITED STATES PATENT OFFICE.

ROBERT G. BRACKETT, OF ROCHESTER, NEW YORK.

CUTTER-HOLDER.

1,131,818.

Specification of Letters Patent. Patented Mar. 16, 1915.

Application filed December 4, 1913. Serial No. 804,649.

To all whom it may concern:

Be it known that I, ROBERT G. BRACKETT, of Rochester, in the county of Monroe and State of New York, have invented certain new and useful Improvements in Cutter-Holders; and I do hereby declare the following to be a full, clear, and exact description of the same, reference being had to the accompanying drawings, forming a part of this specification, and to the reference-numerals marked thereon.

My invention relates to tool or cutter holders, and it has a more particular bearing upon edge working machinery involving devices for holding blades and cutters such as are employed in shoe manufacture, as for example sole and heel trimmers, and it has for its object to provide a simple construction that will enable the operator to readily hold a tool while it is being ground or sharpened.

A further object of my invention consists in the provision of a novel construction whereby the tool can be efficiently held and operated in proper relation to the edge engaging wheel.

A further purpose of the invention consists in constructing the device in such a manner as to facilitate the removal of one tool and the insertion of another, thus resulting in a saving of considerable time where a large number are to be operated on.

To these and other ends the invention consists in certain improvements and combinations of parts all as will be hereinafter more fully described, the novel features being pointed out in the claims at the end of the specification.

In the drawings: Figure 1 is a perspective view, showing an embodiment of my invention, with a tool in position, engaging a grinder which appears partially in dotted lines; Fig. 2 is a side elevation of the end of one of the gripping arms, with the edge gage in operative relation, and Fig. 3 is a sectional view on the line 3—3 of Fig. 1.

Similar reference numerals throughout the several figures indicate the same parts.

In grinding or otherwise sharpening the edges of heel and sole trimmers and similar blades or cutters, it is a difficult matter to maintain the blade in its proper relation to the edge wheel, so as to treat every portion of the edge alike and at the same time obtain a blade having the desired width throughout. In many instances, these blades are held by hand for sharpening, although va-

rious devices have been tried for retaining the blades and affording a convenient holder during the sharpening operation, and it is my purpose to improve the construction of this type of device, so that the blade can readily be moved back and forth laterally of the edge engaging wheel, and the operator can secure a more perfect control over the cutter at every stage of the operation. 60 With this in view, I have devised a construction which is illustrated in the present embodiment, and which preferably comprises an integral strip of stiff, spring metal bent laterally upon itself so as to form a U-shaped member comprising a base portion 1 and gripping arms 2 and 3. By forming the gripping arms from a single strip of metal in the manner set forth, a spring action is constantly exerted upon each arm tending to separate them or move them away from each other, and this enables a blade to be removed very quickly from the holder when the sharpening operation is completed, by merely releasing the hand which is holding 70 the arms in engagement with the tool, and permitting the latter to drop out. It will be understood that during the sharpening operation, the arms are in the position shown in Fig. 1 being held there by a slight pressure of the hand from each side, but when in normal released position, they are spread somewhat, depending upon the resiliency of the metal.

In order to hold the blade properly, I 80 preferably bend the arms 2 and 3 longitudinally upon themselves at the ends, as designated at 4 and 5, forming sockets in which are positioned the removable and adjustable curved jaws 6, the latter being held 85 in place upon the arms by suitable attaching screws 7 secured by the thumb nuts 8. The jaws 6 are curved so as to engage the correspondingly curved slots or recesses 9 which are formed in the edges of the cutters, 100 and the position of the jaws can be adjusted with relation to the gripping arms, so as to secure just the proper engagement with the tool.

If no other support for the tool is provided except the gripping arms, it becomes necessary to hold them quite tightly against the tool, and in order to obviate this and also to prevent any possibility of the tool slipping within the holder, I provide a support for the base of the blade, making such support in the form of an adjustable gage. 110

To this end, I preferably mount a bracket 10 upon the arm 3, securing it rigidly thereto in any desirable manner. The bracket 10 is provided with a threaded opening to receive the adjustable gage in the form of a post 11, carrying the head 12 at its upper end, arranged for engagement with the base of the tool as shown in Fig. 1.

13 is a spring attached to the bracket 10, 10 and arranged to engage the post 11, so as to hold the latter against accidental turning.

The head 12 is milled around its outer edge, and can readily be adjusted to accommodate cutters of different widths, and after 15 once adjusting the gage, it serves to determine the width of the blades to be ground.

In operation, the tool is inserted until it rests upon the adjustable gage 12, and is then ground until its edge is adjacent to a 20 second gage, mounted upon one of the gripping arms. In the present instance, the last mentioned gage is indicated at 14, being adjustably held in position on the arm 3 by means of the thumb nut which also holds 25 the corresponding jaw. In order to afford a convenient means for moving the tool back and forth upon the edge engaging wheel, I attach to the base 1 of the holder, a curved bearing designated at 15, and 30 adapted to rest in a correspondingly curved socket in the support 16 which may be adjustably secured upon the table 17.

It will be understood that while I have disclosed a preferred embodiment of my invention, I am not limited to the particular construction shown and described, since 35 this may be modified as to various details, without departing from the essential features of the invention as comprehended in 40 the claims hereinafter.

I claim as my invention:

1. A tool holder embodying an integral strip of metal bent upon itself and forming a pair of oppositely arranged gripping arms 45 normally tending to move away from each other.

2. A tool holder embodying an integral

strip of metal bent laterally upon itself and forming a pair of oppositely arranged gripping arms, the strip being bent longitudinally upon itself at the ends and forming 50 jaw engaging portions, and removable jaws held in said jaw engaging portions.

3. A tool holder embodying a pair of oppositely arranged gripping arms, a gage adjustably mounted on one of the arms and adapted to engage the base of a tool, and a second gage carried by one of the arms and adapted to extend to a point adjacent to the 55 cutting edge of the tool.

4. A tool holder embodying a pair of oppositely arranged gripping arms, and a gage adjustably mounted on one of the arms and adapted to engage the base of a tool.

5. A tool holder embodying a pair of 60 gripping arms normally tending to move away from each other, and a gage adjustably mounted on one of the arms and adapted to engage the base of a tool.

6. A tool holder embodying an integral 65 strip of metal bent upon itself and forming a pair of oppositely arranged gripping arms normally tending to move away from each other and a gage adjustably mounted on one of the arms and adapted to engage 70 the base of a tool.

7. A tool holder embodying a pair of oppositely arranged gripping arms, and curved jaws carried by said gripping arms.

8. A tool holder embodying a pair of oppositely arranged gripping arms normally tending to move away from each other, and curved jaws carried by said gripping arms.

9. A tool holder embodying an integral 85 strip of metal bent upon itself and forming a pair of oppositely arranged gripping arms normally tending to move away from each other, and curved jaws carried by said gripping arms.

ROBERT G. BRACKETT.
